Myself J. H. Leyton

UNITED STATES PATENT OFFICE.

ARTHUR W. BROWNE, OF PRINCE'S BAY, NEW YORK, ASSIGNOR TO THE
S. S. WHITE DENTAL MANUFACTURING COMPANY, OF PHILADELPHIA,
PENNSYLVANIA.

DENTAL CHAIR.

SPECIFICATION forming part of Letters Patent No. 519,884, dated May 15, 1894.

Application filed February 5, 1894. Serial No. 499,050. (No model.)

To all whom it may concern:

Be it known that I, ARTHUR W. BROWNE, a citizen of the United States, residing at Prince's Bay, in the county of Richmond and State of New York, have invented a certain new and useful Improvement in Dental Chairs; and I do hereby declare the following to be a full, clear, and exact description of the invention, such as will enable others skilled in the art to 10 which it appertains to make and use the same.

My invention relates to a certain improvement, as hereinafter claimed, in means for imparting a wide range of vertical adjustment to the bodies of dental chairs.

15 In my application for United States Letters Patent, Serial No. 494,848, filed December 27, 1893, are shown improvements of the class to which my present invention relates, and I make no claim herein to features claimed 20 or claimable in my said prior application.

25 In the accompanying drawings which show a suitable embodiment of my improvement, Figure 1 is a view mainly in side elevation, some parts being in vertical section. Fig. 2 is a horizontal section on the line 2 of Fig. 1, on an enlarged scale, showing details of construction.

30 My improvement is represented as applied to a dental chair such as shown in United States Letters Patent No. 197,441, dated November 20, 1877, and No. 483,807, dated October 4, 1892. As in said patents there is provided a support (hereinafter termed the 35 chair body A, said support consisting of the plunger A' having vertically adjustable connection with the base or pedestal A² and actuated by means of the jointed elevating lever A³ and co-operating devices, the lever being jointed to the cylinder B which is adapted to turn horizontally in the pedestal and to be locked therein by the locking lever B'. The 40 vertically adjustable support has no horizontal or turning movement in the cylinder B to which the lifting lever is attached, and the manner of upholding and of lowering the support is as fully explained in the above 45 mentioned patent, No. 197,441.

The chair-body is carried by supplementary elevating and lowering mechanism interposed between it and the main elevating and

lowering support A', so as to increase the range of vertical adjustment of the chair body, and this supplementary elevating and lowering mechanism is constructed and supported as follows: The main elevating and lowering support is provided at its upper end with a suitably attached bracket C rigid therewith having at its outer end in front of the main support a bearing sleeve or supporter 55 D projecting downwardly and parallel with the main elevating and lowering support and serving to carry and guide a vertically adjustable bar or rod E having the gear rack or row of teeth e. A pinion F gearing with this 60 gear rack is secured to a shaft f turning in bearings in the bracket C; the pinion is located between the rack rod and the main support. A sheave or pulley G secured to the pinion shaft has one end of a chain g fastened 65 to its periphery, the other end of the chain being secured to the cylinder B. At its upper end the adjustable rack rod E is provided with the chair body carrier H of the supplementary raising and lowering mechanism, this 70 carrier being fastened in suitable way to the rod. The chair body is jointed to its carrier at h over the main raising and lowering support, so as to be capable of tilting vertically. A detent segment I on the chair body is 75 adapted to be engaged by a suitable lever on the chair body carrier so as to secure the chair body in the position to which it may be tilted. These detent devices may be of any well known suitable construction, and detailed description thereof is not here necessary.

From the above description it will be seen that as the main elevating and lowering support is vertically adjusted the pinion of the 80 supplementary elevating and lowering mechanism turns to raise or lower the rack rod, and elevate or lower the chair body. As the main elevating and lowering support is elevated the chain unwinds from its pulley, the 85 lower end of the chain being held by the non-elevating rotary cylinder; and as said support is lowered the weight of the chair body causes descent of the rack rod, thus turning the pinion and pulley and taking up the chain. 90

I claim as my invention—

The combination of the pedestal or base,

the cylinder supported thereby, the main elevating and lowering support, means for vertically adjusting the support in the cylinder, the bracket rigid with said main support and 5 provided at its outer end with the supporter extending downwardly and parallel with the main support, the vertically adjustable rack rod sustained by said supporter, the pinion gearing with the rack rod and having its shaft 10 mounted in bearings in the bracket of the main support between said support and the rack rod, the pulley on the pinion shaft, the chain secured at its opposite ends to the pul-

ley and cylinder, the chair body carrier at the upper end of the rack rod, the chair body 15 having jointed connection with said carrier, and means serving to tilt the chair body about said jointed connection and secure it in its tilted position, substantially as set forth.

In testimony whereof I affix my signature in presence of two witnesses.

ARTHUR W. BROWNE.
